UNITED STATES PATENT OFFICE.

LIONEL WOLFFSOHN, OF HOBOKEN, NEW JERSEY, ASSIGNOR, BY MESNE ASSIGNMENTS,
TO BIJUR MOTOR APPLIANCE COMPANY, A CORPORATION OF DELAWARE.

ENGINE STARTING DEVICE.

1,278,064.

Specification of Letters Patent.

Patented Sept. 3, 1918.

Application filed July 9, 1914. Serial No. 849,898.

To all whom it may concern:

Be it known that I, LIONEL WOLFFSOHN, a citizen of the United States, residing at Hoboken, in the county of Hudson and State 5 of New Jersey, have invented certain new and useful Improvements in Engine Starting Devices, of which the following is a full, clear, and exact description, such as will enable others skilled in the art to which it applies 10 to make and use the same.

This invention relates to engine-starting apparatus, and with regard to certain more specific features, to an arrangement of parts whereby a smaller pinion may be mounted 15 upon a given shaft than is feasible in prior apparatus.

One of the objects of the invention is to provide an engine-starting apparatus comprising a comparatively high speed-reduction 20 effected through a single pair of gears. Another object is to provide a simple and compact arrangement of driving-shaft, roller-clutch and pinion. Another object is to provide an apparatus of the above type in 25 which a pinion of minimum diameter compared with the diameter of the driving-shaft, may be utilized without sacrificing mechanical strength or durability.

Other objects will be in part obvious and 30 in part pointed out hereinafter.

The invention accordingly consists in the features of construction, combinations of elements and arrangement of parts which will be exemplified in the construction herein- 35 after set forth, and the scope of the application of which will be indicated in the following claims.

In the accompanying drawings, in which 40 is illustrated a preferred embodiment of the several features of the invention,

Figure 1 is a longitudinal view, partly in section, of an engine-starting motor, an engine-driven element, and interconnecting mechanism;

Fig. 2 is a transverse section on the line 2-2, of Fig. 1;

Fig. 3 is an end view of Fig. 1; and

Fig. 4 illustrates a pinion and mounting of a type found in the prior art.

Similar reference characters refer to similar parts throughout the several views of the drawing.

By way of explanation it may be stated that in engine-starting apparatus it has been 55 found advantageous to employ a compara-

tively high speed-reduction between the driving motor and the engine shaft. In apparatus of this type where the fly-wheel is engaged to the starting mechanism, the satisfactory speed-reduction in the starting device must be effected by having the motor-driven pinion small enough, or to effect a part of the reduction between fly-wheel and pinion and the remainder through additional mechanism. The present invention 60 relates more especially to increasing the speed reduction by decreasing the size of the motor-driven pinion.

Referring now more particularly to Figs. 1, 2 and 3, there is illustrated at 1 a motor 70 whose shaft 2 has keyed upon it, as at 3, the internal member 4 of a roller-clutch whose external member 5 is revolvably mounted as at 6 upon the motor shaft 2 and carries adjacent the outer end of an annular portion 7 75 an inwardly extending plate or disk 8 provided with internal teeth 9 adapted to cooperate with the external or spur teeth of the pinion 10, mounted upon the motor shaft 2 loosely for rotation and reciprocation relative thereto. Of course, my invention is not confined to the specific form of clutch shown and described, but any clutch connecting means capable of transmitting power from the motor to the pinion but incapable of 80 transmitting power in the inverse direction, regardless what the position of the pinion, would come within the scope of my invention. With the parts in the position illustrated in Fig. 1 a counter-clockwise rotation 85 of the motor shaft 2 and inner member 4 of the roller clutch causes a similar rotation of the outer member 5 of the clutch, and with it its annular portion 7 and inwardly projecting plate 8 and through the 90 annular teeth 9 the pinion 10 is caused to rotate likewise in a counter-clockwise direction, to start the engine by turning the fly-wheel clockwise. If while the pinion is thus 95 in engagement with the fly-wheel gear 11 the engine starts to rotate under its own power, the engine speed may exceed the free running speed of the motor, in which case the pinion 10, plate 8 and outer member 5 of the roller clutch would be driven from the 100 engine, at a speed higher than the speed of the inner member 4 of the clutch. At such time the rollers 12 will simply enter the deeper portions of their respective grooves 13, and the increased speed of the engine will 105 110

not be communicated to the motor. The motor will then ordinarily be disengaged from the engine by releasing the spring-retracted yoke 14, moving the pinion 10 axially 5 toward the left (Fig. 1) through the operative connection between this yoke and the grooved portion 15 of the pinion 10; the axial length of the pinion is preferably greater than its axial travel so that the pinion 10 teeth are in mesh with the annular teeth 9 of the plate 8 regardless of the position of the pinion along the motor shaft. If desired, this movement of the pinion into and out of engagement with the fly-wheel may be 15 effected in suitable time relation to the starting and stopping of the motor itself, as illustrated in my co-pending application Serial No. 775,670, filed June 25, 1913. This may be brought about by the arrangement dia- 20 grammatically indicated in Fig. 1 of the drawings. In this arrangement lever 14 is provided with a contact plate 20 suitably insulated as at 21. This contact plate with the lever in the position shown short circuits 25 the stationary contacts 22, thus completing the circuit 23 between the motor 1 and the source of current 24 by which the motor is driven. The precise time at which this circuit is completed depends of course on the 30 position of the lever 14 when contact 20 is brought against contacts 22 and this may be at any desired stage of the operation.

With the arrangement of parts herein described the radius of the pinion is equal to 35 the sum of the radius of the motor shaft, the web 16 of the pinion and the height of the teeth; further, since no key-ways need to be cut into the web of the pinion, the entire thickness of the web contributes toward the 40 strength of the pinion, and the thickness need, of course, be considerably less than in constructions (see Fig. 4) where it is necessary to weaken the pinion 17 by using part of the web 18 for one or more key-ways 19; 45 so that with apparatus embodying the present invention a maximum speed reduction is secured between engine fly-wheel and motor shaft with given diameters for these two elements. By subdividing the driving power 50 transmitted at the roller-clutch into four portions, and at the pinion into as many portions as there are teeth, the bending and other strains incident to the transmission of power in this manner are far more effectively 55 and safely cared for than would be the case if the entire power had to be transmitted through one or two comparatively shallow key-ways; this advantage results in each instance not only from the subdivision of the 60 coating driving and driven elements, but from the comparatively large effective radius at which these elements contact, the torque transmitted being of course inversely proportionate to the effective radius of a given 65 amount of power. It will thus be seen that

with the present construction the diameter of the pinion is made only slightly in excess of the diameter of the motor shaft without sacrificing strength of parts, compactness, or the advantages gained by the use of 70 a roller clutch.

As many changes could be made in the above construction and many apparently widely different embodiments of this invention could be made without departing from 75 the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of 85 the invention which, as a matter of language, might be said to fall therebetween.

Having described my invention, what I claim as new and desire to secure by Letters Patent is:

1. Apparatus of the character described, comprising, in combination, a motor, an engine-driven member, a motor-driven member mounted for rotation and reciprocation with respect to its support, an over-running 95 clutch comprising a member secured to the motor shaft and a member revoluble upon said shaft, and a power-transmitting connection between said last-named member and said motor-driven member.

2. Apparatus of the character described, comprising, in combination, a motor, an engine-driven member, a motor-driven member, an over-running clutch through which power is transmitted from said motor to 105 said motor-driven member, and means for moving said motor-driven member into engagement with said gear simultaneously with the application of power to said motor.

3. Apparatus of the character described, comprising, in combination, a motor, an engine-driven member, a motor-driven member, an over-running clutch through which power is transmitted from said motor to said 115 motor-driven member, means for moving said motor-driven member into engagement with said gear simultaneously with the application of power to said motor, and means for energizing said motor fully subsequent to engagement.

4. Apparatus of the character described, comprising, in combination, a motor, an engine-driven gear, a motor-driven member, an over-running clutch through which power is transmitted from said motor to said motor- 125 driven member, and means for moving said motor-driven member into engagement with said gear simultaneously with the application of power to said motor, said clutch overrunning when said engine-driven gear has 130

started and prior to disengagement of said gear and pinion.

5. Apparatus of the class described comprising, in combination, an engine-driven gear, a motor-driven shaft, a pinion mounted upon said shaft to move into mesh with said gear, and means adapted to transmit power from said shaft to said pinion at a point more remote from the axis of said shaft than the base of the pinion teeth.

6. Apparatus of the character described, comprising, in combination, a motor, a motor shaft, an engine-driven gear, a pinion mounted on the motor shaft adapted to mesh with said gear, and a power-transmitting connection between the motor shaft and the teeth of said pinion independent of the body of said pinion.

7. Apparatus of the character described, comprising, in combination, a motor, a motor shaft, an engine-driven gear, a pinion rotatably mounted sleeved directly on the motor shaft adapted to mesh with said gear, a power-transmitting connection between the motor shaft and the teeth of said pinion, and means adapted to cause said pinion to travel into and out of mesh with said gear.

8. Apparatus of the character described, comprising, in combination, a motor, a motor shaft, an engine-driven member, a motor-driven member mounted on the motor shaft adapted to make power-transmitting connection with said engine-driven member, an over-running clutch comprising a member secured to the motor shaft and a member revolute upon said shaft, and a power-transmitting connection between said last-named member and said motor-driven member at a point laterally offset from said engine-driven member at all positions of said motor-driven member.

9. Apparatus of the character described, comprising, in combination, a motor, an engine-driven member, a motor-driven member adapted to coat with said engine-driven member and sleeved on the motor shaft, and power-transmitting means comprising an overrunning clutch and having a portion extending radially beyond said motor-driven member through which power is transmitted to the latter.

10. Apparatus of the character described, comprising, in combination, a fly-wheel, a gear on said fly-wheel, a motor-driven pinion, and an over-running clutch comprising a member secured to the motor shaft and a member revolutely mounted on said shaft and provided with an inwardly extending portion adapted to engage the teeth of said pinion.

11. Apparatus of the character described, comprising, in combination, a fly-wheel, a gear on said fly-wheel, a motor-driven pinion sleeved on the motor shaft, and an overrunning clutch comprising a member secured

to the motor shaft and a member revolutely mounted on said shaft and provided with an inwardly extending portion adapted to engage the teeth of said pinion.

12. Apparatus of the character described, comprising, in combination, a motor, an engine-driven gear, a motor-driven pinion, an over-running clutch comprising a member secured to the motor shaft and a member revolutely mounted on said shaft and provided with an inwardly extending portion adapted to engage the teeth of said pinion continuously, and means for moving said pinion axially to effect a driving engagement between said pinion and said gear.

13. Apparatus of the character described, comprising, in combination, a motor, a motor shaft, an engine-driven member, a pinion sleeved directly on the motor shaft, an over-running clutch comprising a member secured to the motor shaft and a member revolute upon said shaft, and a power-transmitting connection between said last-named member and the teeth of said pinion.

14. Apparatus of the character described, comprising, in combination, a motor, an engine-driven gear, a shaft driven from said motor, a pinion on said shaft normally out of mesh with said gear and adapted to be moved into mesh therewith, and means driven from said motor and adapted to embrace and drive said pinion.

15. Apparatus of the character described, comprising, in combination, a motor, an engine-driven gear, a shaft driven from said motor, a pinion on said shaft normally out of mesh with said gear and adapted to be moved into mesh therewith, and a device driven from said motor fitting about said pinion and interlocking with teeth thereon.

16. Apparatus of the character described, comprising, in combination, a motor, an engine-driven gear, a shaft driven from said motor, a pinion on said shaft normally out of mesh with said gear and adapted to be moved into mesh therewith, and a device driven from said motor fitting about said pinion and interlocking with teeth thereon, said pinion being slidable within the member fitted about the same.

17. Apparatus of the character described, comprising, in combination, an engine-driven gear, a motor, a pinion, a member adapted to transmit power from said motor to the teeth of said pinion, at one part of the length of said teeth, another part of said teeth being adapted to engage said gear, and means adapted to move said pinion into and out of mesh with said gear.

18. Apparatus of the character described, comprising, in combination, an engine-driven gear, a motor, a pinion, means adapted to transmit power from said motor to the teeth of said pinion, means adapted to move said pinion into and out of mesh with

said gear, said means including a clutch through which power is transmitted to said pinion.

19. Apparatus of the character described, comprising in combination, an engine-driven gear, a pinion, means adapted to move said pinion into and out of mesh with said gear, and a driving member for said pinion fitted about and interlocking with the teeth there-
10 of and with respect to which said pinion is
slidable in an axial direction.

20. Apparatus of the character described, comprising in combination, an engine-driven gear, a pinion, means adapted to move
15 said pinion into and out of mesh with
said gear, a driving member for said pinion
fitted about and interlocking with the teeth
thereof and with respect to which said pin-
ion is slidable in an axial direction, a motor,
20 and means adapted to transmit power from
said motor to said pinion through a clutch.

21. Apparatus of the character described, comprising in combination, a pinion, a mem-
ber fitted about said pinion and interlock-
ing with the teeth thereof and with respect 25
to which said pinion is slidable, and means
adapted to drive said pinion through said
member.

22. In apparatus of the class described,
in combination, an engine, a driven gear 30
connected with said engine, a driving gear
adapted to coöperate therewith, and means
driven by a starting motor, and coöperating
with said driving gear at a point spaced
from its mount.

35 In testimony whereof I affix my signature,
in the presence of two witnesses.

LIONEL WOLFFSOHN.
